BALLINGER, TEXAS

CONVEYER BEARING

Application filed May 5, 1930. Serial No. 450,051.

The present invention relates to shaft bearings of the pedestal type, particularly for horizontal or other non-vertical shafts of screw conveyers; and it has for its object to produce a simple and novel bearing of this type which is readily acceptable for purposes of adjustment and repair.

The present invention is particularly applicable as a bearing for the shaft of a conveyer running in a box open at the top; and may therefore be said to have for one of its objects to produce a bearing for this purpose which will take up the minimum amount of space in the box and permit adjustment and replacement of the actual bearing elements in a simple manner and without first disconnecting the conveyer or requiring the bearing pedestal to be disturbed, and which will permit the conveyer to be removed from the box without disturbing the bearing pedestal or discontinuing the conveyer sections.

The various features of novelty whereby our invention is characterized will herein-after be pointed out with particularity in the claims; but, for a full understanding of our invention and of its objects and advantages, reference may be had to the following detailed description taken in connection with the accompanying drawing, wherein:

Figure 1 is a transverse section through a conveyer box having therein a conveyer supported by a bearing embodying the present invention; Fig. 2 is a section on line 2—2 of Fig. 1; and Fig. 3 is a section on an enlarged scale on line 3—3 of Fig. 2.

Referring to the drawing, 1 represents the box or casing, and 2 the spiral flights of a screw conveyer shown as fixed to a shaft 3 extending lengthwise through the casing. The casing is shown as being open at the top and having in the bottom corner boards 4. As explained in our prior application, Serial No. 220,280, the shaft may be supported most advantageously upon a pedestal below the same and inclined to a vertical plane containing the long axis of the shaft in the opposite direction from the direction of rotation of the screw. In an apparatus of this kind, the pedestal may conveniently extend between one of the inclined corner boards

and the shaft. In the arrangement shown, there is such a pedestal, in the form of a comparatively slender hollow column 5 having a wide base flange 6 resting on one of the corner boards and continuing beyond the same so as to engage with the adjacent side wall of the casing, and also with the bottom wall of the casing. Bolts 7 may conveniently be employed to secure the flange to the side and bottom walls of the casing. The pedestal is open at the top and has a long slot 8 extending throughout the length of one side wall, at about the middle of the latter. There is an outwardly projecting flange 9 at the upper end of the pedestal, on the side that has the slot therein. The opposite side wall is continued outwardly or upwardly a considerable distance beyond the outer or upper face of the flange, as indicated at 10, and is provided with an inwardly facing hook or hooks 11. 12 is a cap shaped at one end to be engaged with the hook or hooks and to rest at its other end upon the flange 9.

Within the pedestal is a bearing block 13, preferably of wood. The shaft to be supported rests between and is engaged by the bearing block and the inner or under side of the cap; the bearing seat in the block being semi-cylindrical, or of smaller angular extent, so that when the cap is removed the shaft may be lifted out of the bearing without disturbing the body portion of the pedestal or the bearing block.

A single bolt device is employed to support the bearing block, hold the cap in place, and provide adjustment for taking up wear. This bolt, indicated at 14, extends along the slot 8 in the pedestal and has at its lower or inner end an arm 15 that underlies the bearing block. The extreme end of the arm is preferably bent up, as indicated at 16, and is entered in a pocket or recess 17 in the bottom face of the bearing block, whereby separation of the bolt from the bearing block through a lateral movement will be prevented as long as what may be termed the projection on the bolt remains in the socket in the under side of the bearing block. The bolt extends up through the flange 9 and through an opening in that part of the cap that overlies the

90

95

100

flange. On the upper end of the bolt is a nut 18 which preferably has a conical under face 19 fitting into a correspondingly shaped seat in the bearing cap.

5 When the parts are assembled as shown, and the nut is tightened, the bearing block is drawn up against the shaft and the bearing cap is drawn downwardly or inwardly against the flange on the pedestal. After the cap has

10 been drawn firmly into an engagement with the flange it can move no farther, and, therefore, any further relative movement between the cap and the block must be through a movement of the block along the pedestal.

15 Therefore, as wear takes place, in use, the slack is taken up by tightening the nut and drawing the block upward.

When it is necessary to renew the bearing, all that need be done is to unscrew the single 20 nut, lift off the cap, and then raise the conveyer shaft by lifting the screw out through the top of the box; thus exposing the bearing block and permitting its withdrawal, without disturbing the body portion of the pedestal.

25 In this way, also, the conveyer may be removed from the box for convenience in repairing, without disturbing the bearing pedestal or disconnecting the conveyer sections.

30 While we have illustrated and described with particularity only a single preferred form of our invention, we do not desire to be limited to the exact structural details thus illustrated and described; but intend to cover all forms and arrangements which come within 35 in the definitions of our invention constituting the appended claims.

We claim:

1. The combination with the casing and the shaft of a screw conveyer, of a pedestal within 40 the casing radial to the screw shaft and inclined laterally and downwardly, the pedestal being hollow and open at the top, a bearing block in the pedestal having in the top a seat engaged with said shaft, a detachable bearing cap having in its under side a seat 45 engaged with said shaft, and a fastening device holding the cap down against the upper end of the pedestal and drawing the block up against the shaft.

50 2. The combination with the casing and the screw of a screw conveyer, of a pedestal within the casing radial to the screw shaft and inclined laterally and downwardly, the pedestal being hollow and open at the top, a bearing block in the pedestal, a detachable bearing cap, and a fastening device, including a nut above the pedestal, for holding the cap down against the upper end of the pedestal and drawing the block up against the shaft.

55 3. The combination with the casing and the screw of a screw conveyer, of a pedestal within the casing radial to the screw shaft and inclined downwardly and laterally, the pedestal being hollow and open at the up-

per end, a bearing block slideable in the pedestal, a bearing cap above the pedestal and resting thereon on one side of the shaft, interlocking shoulders between the pedestal and the cap on the other side of the shaft, and 70 means for simultaneously drawing the block up against the shaft and the bearing cap down upon that part of the pedestal on which it rests.

4. The combination with the casing and 75 the screw of a screw conveyer, of a hollow open top pedestal within the casing radial to the screw shaft and inclined downwardly and laterally, a bearing block in the pedestal, a flange at the top of the pedestal on one 80 side of the shaft, a bearing cap resting on the flange, interlocking shoulders on the bearing cap and pedestal on the opposite side of the shaft, a bolt extending through the cap and flange and down along the pedestal, a 85 part on the lower end of the bolt underlying the block, and a nut on the upper end of the bolt.

5. A device of the character described comprising a hollow pedestal open at one 90 end, a bearing block slideable in said pedestal, a cap resting on the open end of the pedestal, and a fastening device for drawing said block toward the cap and holding the cap down on the pedestal. 95

6. A device of the character described comprising a hollow pedestal open at one end, a bearing block slideable in said pedestal, said pedestal having a laterally projecting flange on one side at the open end, a cap resting on the flange, the cap and the side of the pedestal opposite that on which the flange is located having interlocking shoulders, there being a slot extending lengthwise of the pedestal in the flanged side, a bolt extending along said slot and through said flange and the overlying part of the cap, a nut on one end of the bolt, and a part on the bolt interlocked with the end of the block remote from the cap. 100

7. A device of the character described comprising a hollow pedestal open at one end, a bearing block slideable in said pedestal, a bearing cap resting on said end, a member extending lengthwise of the pedestal and through said cap, said block and said cap having bearing seats adapted to receive a shaft between the same, a shoulder on said member engaged with the end of the block remote from said cap, and a part screw threaded on said member and engaged with the cap to draw the block and the cap toward each other. 115

8. A device of the character described comprising a hollow pedestal open at one end and having on one side at said end a flange and at the other side a hook extension projecting beyond the plane of the flange, a bearing block in said pedestal and slideable lengthwise thereof, a bearing cap engaged at 120 130

one end with said hook extension and resting at its other end on said flange, a bolt extending through said cap and flange and along the pedestal to the remote end of the block, a part on said bolt underlying the block, and a nut on the end of the bolt beyond the cap.

5 In testimony whereof, we sign this specification.
